(57) **CLAIM**

The ornamental design for an enclosure for a wireless siren sensor with strobe light, as shown and described.

DESCRIPTION

FIG. 1 is a perspective view of the enclosure.

FIG. 2 is a front elevation view thereof; and,

FIG. 3 is a side elevation view thereof, the mirror images being the same.

The rear view of the enclosure illustrated in FIGS. 1-3 is hereby disclaimed and forms no part of the claimed design.
